UNITED STATES PATENT OFFICE.

EMORY M. FOSTER, OF SOUTHGATE, CALIFORNIA.

SPRAYING MACHINE.

Application filed June 8, 1927. Serial No. 197,481.

This invention relates to spraying devices, and in particular to tree and plant husbandry, and it is an object of the invention to provide a spraying device that will effectively spray vegetation, whether the liquid used in spraying be a pure solution, emulsion, suspension or semi-solid. It is a well known fact that tobacco leaves, when placed in water, impart their poisonous secretions to the water, and 5 the solution is quite effective as a spray for vegetation to kill various insects and prevent certain growths on the vegetation. Heretofore, it has been practically necessary to strain the leaves from the tobacco before placing 10 the same in a spraying device, as the narrow nozzle required to impart an effective spray to the liquid easily becomes clogged up, and if a screen is used on the passage-way leading to the nozzle, this screen becomes 15 clogged with impurities and will not permit liquid to pass therethrough.

It is an object of this invention to provide a device wherein this difficulty has been remedied, and suspension of tobacco leaves and 20 water may be employed in the device with little danger of clogging the spraying nozzle.

A still further object of this invention is to provide a device which is inexpensive to manufacture, is effective in its operation, and is 25 well adapted to perform its required services.

With these and many other objects in view, which will more readily appear as the nature of the invention is better understood, the same consists in the novel construction, combination 30 and arrangement of parts, which will hereinafter be more fully described, illustrated, and claimed.

The essential features of the invention involved in the carrying out of the objects indicated are susceptible to modification; but a preferred embodiment of the invention is 35 shown in the accompanying drawings, in which:

Figure 1 is a side view of the device showing 40 certain parts broken away to more clearly reveal the nature of the invention.

Fig. 2 is a sectional view taken laterally through the device.

Referring to the accompanying drawings, 45 in which similar reference characters designate similar parts throughout, the figures described above adequately illustrate my invention, and the following detailed description is commensurate with the above mentioned 50 drawings in enabling an artisan to construct

and assemble the constituent parts of the same.

The device involves in its general organization a jar 10, which jar is of any suitable design and may be formed of any suitable material, but is preferably formed of glass. This jar has a cover 11 threadedly receivable thereon, and disposed between the jar and cover is a packing washer 29, and extending through this cover 11 are a plurality of apertures 12, 13 and 27. A screen 28 extends across the aperture 27. A cap 14 is mounted on the cover 11. An air discharge duct 15 extends into the cap 14, and an outlet tube 16 extends from a point adjacent the bottom of the jar 60 through the cover 11 and the cap 14 and tube 15, to the atomizer 26. A small screen assembly 17 is secured to the lower end of the tube 16. The tube 16 is bent as at 18 so as to permit the screen assembly 17 to assume an inclined position. A small section of tubing 19 extends through the aperture 12 in the cover 11 and through the cap 14, and receives an elbow 20 at its upper end. An inlet tube 21 extends downwardly into the jar to a point 65 just beneath the screen assembly 17, and is attached to the lower end of the tube section 19. A check valve 22 is placed in the lower end of the tube 21. The conventional type of plunger pump is designated at 23 and has its 70 discharging outlet 24, threadedly receivable in the elbow 20. The end of the discharge duct 15 is provided with an atomizer 26 which is threadedly receivable upon this member. The tube 16 extends outwardly through the 75 cap 14 and is bent to extend through the member 15 and is spaced from the walls thereof. In order to properly space this tube 16, a coil 80 spring is disposed about the same within the member 15. This coil spring is designated 85 at 40.

In manufacturing the device, in order to effect the proper adjustment of the member 15 and the tube 16, the tube 16 and coil spring are first inserted in the member 15 before the 90 same is bent, and when the parts are thus assembled, it is a comparatively easy matter to bend the member 15 so as to have a horizontal arm, and in bending, the coil spring prevents contact of the tube 16 with the walls of the 95 member 15, and incidentally serves to reinforce the same.

The above parts are thought to adequately define my invention in such a manner as to enable anyone skilled in the art to manu- 100 105 110

facture the same, and I will now proceed with a full detailed description of the operation of the device so as to enable a person skilled in the art to use the same.

- 5 When the parts are in assembled relationship as clearly shown in the figures of the drawings, and air is forced into the jar by means of the plunger pump, the check valve 22 will prevent air or fluid from returning to 10 the plunger by way of the tube 21, and the solution will be forced into the tube 16, and to the atomizer 26. Air which has been compressed within the jar will pass through the screen 27 into the cap 14 and thence through 15 the tube 15, following the spiral path of the helical coil spring 40 to the atomizer 26, wherein it will mix with the liquid issuing from the tube 16 and divide it into a fine spray. A jet of air issuing from the check valve 22 will be forcibly thrown against the screen and will tend to clear the same of particles of foreign matter that would otherwise tend to clog the tube 16 and prevent proper operation of the device.
- 20 25 I do not desire to limit myself to the use of this device for disinfectant purposes alone, or for use upon vegetation, as I find that the device is well adapted for spraying paints, glue or the like. When the device is to be used for spraying paint, it will be readily apparent that the jet of air issuing from the check valve 22, in addition to clearing the screen 17 and preventing clogging of the tube 16, will keep the paint at all times in an agitated condition, preventing the heavy pigment in the paint from settling to the bottom.
- 30 35 It will be further apparent that various changes in the details of construction may be resorted to. For example, when in use for spraying paint, the pump assembly 23 may be completely removed, and in its stead, there may be inserted the conventional type of air compressor line.
- 40 45 From the foregoing, it is thought that the construction, use and many advantages of the herein-described spraying machine will be adequately understood. It will be further understood that certain material alterations

in the construction may be effected without 50 having a deleterious effect upon the efficiency of my device. The minor details in the construction will at all times of course, be performed within the scope and spirit of the subjoined claims. 55

What I claim by this invention and desire to secure by Letters Patent, is:

1. A spraying device comprising a receptacle, a cover for said receptacle having an aperture therein, a cap on said cover over said aperture, a tube extending through said cover and cap to a point adjacent the bottom of the receptacle, an open-ended tube concentric with said first mentioned tube extending into said cap, a coil spring disposed between said tubes, a nozzle on said last mentioned tube, means for forcing air into said receptacle, said means comprising a tube assembly extending through said cover and cap to a point adjacent the bottom of the receptacle and means at the lower end of said tube assembly to direct the discharge across the end of the first mentioned tube to clear the end of the first mentioned tube of accumulated solid particles, and a force pump assembly attached to last mentioned tube assembly. 70
2. A spraying device comprising a receptacle, a cover for said receptacle having an aperture therein, a cap on said cover over said aperture, a tube extending through said cover and cap to a point adjacent the bottom of the receptacle, an open-ended tube concentric with said first mentioned tube extending into said cap, a coil spring disposed between said tubes, a nozzle on said last mentioned tube, means for forcing air into said receptacle, said means comprising a tube assembly extending through said cover and cap to a point adjacent the bottom of the receptacle, a force pump assembly attached to last mentioned tube assembly, a screen on said first mentioned tube, said second mentioned tube assembly extending to a point adjacent said screen, and a check valve on the end of said tube assembly for the purpose specified. 90

In testimony whereof I have signed my name to this specification.

EMORY M. FOSTER.
